US00D745146S

(12) **United States Design Patent**
Hess et al.(10) **Patent No.:** US D745,146 S
(45) **Date of Patent:** ** Dec. 8, 2015(54) **SURGICAL SUTURING DEVICE**

(71) Applicant: **Ethicon Endo-Surgery, Inc.**, Cincinnati, OH (US)

(72) Inventors: **Christopher J. Hess**, Cincinnati, OH (US); **James G. Lee**, Cincinnati, OH (US); **Daniel J. Mumaw**, Liberty Township, OH (US)

(73) Assignee: **Ethicon Endo-Surgery, Inc.**, Cincinnati, OH (US)

(**) Term: **14 Years**

(21) Appl. No.: **29/493,229**

(22) Filed: **Jun. 6, 2014**

(51) LOC (10) Cl. **24-02**

(52) U.S. Cl.

USPC **D24/133; D24/145**

Primary Examiner — Wan Laymon
Assistant Examiner — Mark Booker

(57) **CLAIM**

The ornamental design for a surgical suturing device, as shown and described.

DESCRIPTION

FIG. 1 is a perspective view of a surgical suturing device; FIG. 2 is a top plan view thereof; FIG. 3 is a right side elevation view thereof; FIG. 4 is a bottom plan view thereof; FIG. 5 is a front elevation view thereof; and, FIG. 6 is an end elevation view thereof.

The broken lines shown in the drawings are included for the purpose of illustrating structural environment and form no part of the claimed design.

1 Claim, 3 Drawing Sheets
